UNITED STATES PATENT OFFICE.

EDWIN M. ROSENBLUTH, OF PHILADELPHIA, PENNSYLVANIA.

DESIGN FOR A LAMP-BODY.

SPECIFICATION forming part of Design No. 34,571, dated May 28, 1901.

Application filed April 17, 1901. Serial No. 56,328. Term of patent 7 years.

To all whom it may concern:

Be it known that I, EDWIN M. ROSENBLUTH, of Philadelphia, in the State of Pennsylvania, have invented and produced a new and original Design for Lamp-Bodies, whereof the following is a specification, reference being had to the accompanying drawing.

The drawing shows a side view of a lamp-body embodying my design, which comprises four principal parts—namely, the carbid-chamber A, the water-chamber B, the flame-chamber C, and the chimney D.

The carbid-chamber A is of cylindrical form, disposed with its axis in vertical position, the top *a* of said chamber being of curved contour at its periphery. Between the top *a* of the carbid-chamber and the bottom of the water-chamber is a space *b*.

The lower portion *b'* of the water-chamber B is of cylindrical form concentrically arranged with respect to the carbid-chamber, with its axis in vertical position. The upper portion *b²* of said water-chamber B is arranged in concentric relation with the cylindrical portion *b'* thereof and is of oblate spheroidal form. Between said water-chamber B and flame-chamber C is a cylindrical zone E, which is disposed with its axis in vertical position

in concentric relation with the water-chamber B and is provided with circumferential apertures *e* in its periphery. Said flame-chamber C is of cylindrical form and disposed with its axis in horizontal position, having a convex rear end *c* and an outwardly-flaring front end *c'*. 35

The chimney D consists of an upwardly and outwardly flaring neck *d*, embodying apertures *d'*, an annulus *d²*, embodying apertures *d³*, and a cap *d⁴*, whose crown *d⁵* is of convex form. 40

The carbid-chamber A and water-chamber B are connected by a bracket F, which projects laterally therefrom parallel with the axis of the flame-chamber C and vertically beneath the rear end *c* of the latter. 45

I claim—

The design for a lamp-body substantially as herein shown and described.

In testimony whereof I have hereunto signed my name at Philadelphia, Pennsylvania, this 16th day of April, 1901. 50

EDWIN M. ROSENBLUTH.
